UNITED STATES PATENT OFFICE.

WILLIAM PARKE JOHNSON, OF LINCOLN PARK, NEW JERSEY, ASSIGNOR TO THE FIBERLOID CORPORATION, OF SPRINGFIELD, MASSACHUSETTS, A CORPORATION OF MASSACHUSETTS.

DESIGN FOR BOX-COVER PAPER.

Application filed May 21, 1924. Serial No. 9,691. Term of patent 3½ years.

To all whom it may concern:

Be it known that I, WILLIAM PARKE JOHNSON, a citizen of the United States, residing at Lincoln Park, in the county of Morris and State of New Jersey, have invented a new, original, and ornamental Design for Box-Cover Paper, of which the following is a specification, reference being had to the accompanying drawing, forming a part thereof.

The figure is a view of a sheet of paper showing my new design.

The lines indicate a contrasting color to that of the body of the paper on which the design is displayed.

I claim—

The ornamental design for box cover paper as shown and described.

WILLIAM PARKE JOHNSON.
